AUTOMATIC PHONOGRAPH RECORD
CHANGER

Harald Valdemar Alexandersson, Lidingo, Sweden, assignor to Aga-Baltic Aktiebolag, Stockholm, Sweden, a corporation of Sweden

Application February 9, 1943, Serial No. 475,246
In Sweden August 22, 1942

3 Claims. (Cl. 274—15)

1

My invention relates to automatic record-changers for phonographs.

In devices of this type it is necessary that, after the record-changing having been completed, the tone arm carrying the needle should be lowered in such a way that the latter enters the initial groove of the new record. However, it is known that the actual diameter of different records may vary a few millimeters even if the records are said to have the same diameter, and further that the edge spacing on the records, which does not contain any reproduction groove, may also vary in width a few millimeters. Consequently, if the needle is always lowered on to the record at the same radius, independently of the actual diameter of the latter, it may occur that the needle is lowered into the second, third or even the fourth turn of the reproduction groove if the groove begins too far out on the record, whereas in the opposite case the needle may be lowered on to the edge part of the record, which does not contain any reproduction groove. In the former case the beginning of the music will not be reproduced, whereas in the opposite case the needle may run a plurality of turns on the smooth edge part without entering the groove. Dependent upon the angle of incidence of the tone arm against the record it may even occur that the needle will continuously remain on said smooth edge part or be thrown outwards, so that it falls down on the turntable, in which case there is danger of tearing the felt covering of the latter.

In newer records, in order to avoid this difficulty, there is often provided a so-called entrance groove, which extends with a greater than normal pitch from the outmost edge of the record to the initial turn of the reproduction groove. Hence, if the needle is lowered into the smooth edge, it hits this entrance groove as the record is rotated, and is thus guided inwards to the reproduction groove.

As a rule the last named arrangement is a sufficient means for preventing damage to the felt on the turntable. On the other hand it means a certain delay added to the time required by the record-changing itself. Finally, it is frequently desired to play older records which are not provided with such an entrance groove.

The present invention refers to an arrangement in connection with the record-changer itself, by which the needle is given an impulse for moving it towards the centre of the record. The invention is applied to record-changers in which the movement of the tone arm is controlled by means of a cam disc, a groove disc or the like. Such

2

cam or groove discs are usually divided in two different parts, radially separated from each other. One part contains the cam surface or the groove by means of which the swinging out and inwards of the tone arm during the record-changing is controlled, whereas the other part frees the tone arm for movement so that the needle may follow the spiral groove during the reproduction of the record.

According to the invention, there is arranged 10 a spring on the cam disc, which is placed at the end of the cam surface or groove which moves the tone arm during record changing the spring being arranged to strike the cam follower which 15 controls the tone arm, so as to give the follower and hence the arm an impulse for movement towards the centre of the record. This impulse, however, is not strong enough to move the tone arm if the needle has entered the groove in the 20 record.

The invention is further described on the annexed drawing, in which Fig. 1 is a plan view of the essential parts of an automatic record-changing arrangement in accordance with the present 25 invention, whereas Fig. 2 shows an enlargement of a detail of the arrangement according to Fig. 1.

In the arrangement shown in the drawing, it is assumed that the movement of the sweep arm 10 is controlled by means of a cam disc 11, turnable 30 about a centre pin 12. In well-known manner the cam disc is rotated during the record-changing in the direction of the arrow 13 by means of a roller 14 driven by the phonograph motor, which roller rides up on to the surface 15 of the cam disc 11. During the reproduction of the record 35 the disc 11 is stationary, the roller 14 rotating freely in a recess 16 in this surface. The control of the arm 10 by means of the groove 17 in the cam disc takes place by means of a cam follower 40 in the form of a pin 18, which is connected to an arm 20 pivotable about a point 19. The arm 20 is by means of a link 21 connected to the sweep arm 10.

In the position shown in the drawing the pin 18 45 is in the enlarged part 22 of the groove, which permits free movement of the sweep arm 10 during the reproduction of the record. After a record has been reproduced the cam disc 11 is rotated in the direction of the arrow 13, whereby the pin 18 is guided into the opening of the groove 17 and follows this groove into one of the groove 50 parts 23 or 24, dependent upon the position of a track switch member 25. The last named arrangement is provided in order to properly position the tone arm for playing small or large rec- 55

ords. The arrangements for the control of the track switch 25 form no part of the present invention.

According to the invention, however, in the place where the groove parts 23 and 24 open into the enlarged part 22 there are arranged springs 26 and 26', respectively, for each of the two groove parts, the arrangement of which is more evident from the detail Figure 2, which shows one of the springs.

In the form of execution of the invention shown in Fig. 2 the cam disc 11 is provided with a pin 27 and an opening 28. One end of the spring 26 is bent angularly and extends into the opening 28, whereby this end of the spring is fixed against pivotal movement about the pin 27. The spring is wound one or more turns spirally about the pin 27, and its other end extends fully or partly across the end of the groove 23 or 24, respectively. The spring 26 is of such strength that it gives the pin 18 an impulse for movement towards the centre of the cam disc 12 immediately after it leaves one of the grooves 23 or 24 and as it enters the enlarged part 22, which impulse is transferred to the arm 10 which indirectly moves the reproduction needle. Consequently, the latter is moved inwards until it is stopped by the outmost reproduction groove of the record.

Of course, the invention is not limited to the form of execution shown in the figure in detail and described in the specification, but certain modifications may be made which will be evident to the man skilled in the art and the invention, of course, comprises all such modified arrangements.

What is claimed is:

1. For use in a phonograph of the record changer type for moving the phonograph needle into the first sound groove, a cam disc having a cam groove therein, a cam follower for operating in said groove, said groove having a portion of narrow gage for confining said follower to a precise path of travel, and having a portion of wider gage permitting greater movement of said follower, a spring located adjacent the junction of said portions and extending obliquely inward across the path of travel of said follower immedi-

40

45

ately after the latter has left said portion of narrow gage and has entered said portion of wider gage whereby said follower is given an impulse tending to resiliently move it inwardly.

5. For use in a phonograph of the record changer type for moving the phonograph needle into the first sound groove, a cam disc having a cam groove therein, a cam follower for operating in said groove, said groove having a portion of narrow gage for confining said follower to a precise path of travel, and having a portion of wider gage permitting greater movement of said follower, a pin carried by said cam disc adjacent to said juncture, a recess in said disc spaced from said pin in a direction away from said portion of wide gage, a spring member having a coiled central part embracing said pin, one end portion of said spring extending into said recess and the other end portion of the spring extending obliquely inward across the path of travel of said follower immediately after the latter has left said portion of narrow gage and has entered said portion of wider gage whereby said follower is given an impulse tending to resiliently move it inwardly.

2. For use in a phonograph of the record changer type for moving the phonograph needle into the first sound groove, a cam disc having a cam groove therein, a cam follower for operating in said groove, said groove having a portion of narrow gage for confining said follower to a precise path of travel, and having a portion of wider gage permitting greater movement of said follower, a pin carried by said cam disc adjacent to said juncture, a recess in said disc spaced from said pin in a direction away from said portion of wide gage, a spring member having a coiled central part embracing said pin, one end portion of said spring extending into said recess and the other end portion of the spring extending obliquely inward across the path of travel of said follower immediately after the latter has left said portion of narrow gage and has entered said portion of wider gage whereby said follower is given an impulse tending to resiliently move it inwardly.

3. For use in a phonograph of the record changer type for moving the phonograph needle into the first sound groove, control mechanism comprising a body having means defining a path of travel and including a portion of narrow gage and a portion of wider gage, a follower arranged to travel in said path, spring means disposed adjacent the junction of said portions obliquely inward across the path of travel of said follower immediately after it has left the portion of narrow gage and has entered the portion of wider gage for imparting an impulse tending to resiliently move said follower inwardly of said path.
